E. MAKER.
SAFETY CARRYING BAND.
APPLICATION FILED DEC. 15, 1916.

Patented Aug. 7, 1917.

W. A. Sawyer, Attorneys.

UNITED STATES PATENT OFFICE.

ERNEST MAKER, OF SANTA ROSA, CALIFORNIA.

SAFETY CARRYING-BAND.

1,235,582.

Specification of Letters Patent. Patented Aug. 7, 1917.

Application filed December 15, 1916. Serial No. 137,224.

To all whom it may concern:

Be it known that I, ERNEST MAKER, a citizen of the United States, residing at Santa Rosa, in the county of Sonoma and State of California, have invented certain new and useful Improvements in Safety Carrying-Bands, of which the following is a specification.

This invention relates to an improved safety carrying band and has as its primary object to provide a device of this character particularly adapted for adjustable connection about the arm or other part of the person and provided at its free end with a snap for receiving a pocketbook, card case, or other similar article to be safely and easily carried by the said band.

The invention has as a further object to provide the band with a buckle slidably adjustable upon the band for connecting the said band with the arm or other part of the person and wherein the snap upon the free end of the band may be engaged with said buckle to form a loop for receiving the article to be carried by the band.

And the invention has as a still further object to provide an improved mounting for the snap of such nature that the said snap will not be likely to be pulled loose from the band.

Other and incidental objects will appear as the description proceeds and in the drawings wherein I have illustrated the preferred embodiment of the invention and wherein similar reference characters designate corresponding parts throughout the several views:

Figure 1 is a perspective view of my improved band, illustrating the manner in which a conventional type of card case may be connected to the snap of the band to be carried by the said band.

Fig. 2 is a fragmentary perspective view showing the snap of the band engaged with the buckle thereof to form a loop and illustrating a conventional type of powder box engaged with the said loop to be carried by the band.

Fig. 3 is a plan view of the band with the snap end thereof shown in section and illustrating the manner in which the snap is connected with the band, and

Fig. 4 is a transverse sectional view particularly showing the eyelet in the snap end of the band for receiving the link connecting the snap with the band.

In carrying out the invention, a strap or

suspension element 10 of approved length is employed. This strap is formed of fabric or other suitable material and at one end thereof is equipped with a buckle 11 suitably secured to the adjacent end of the strap. The buckle 11 includes a slidable catch 12 provided with a plurality of teeth 13 to co-operate with the free end of the strap.

At its extremity opposite the buckle 11, the strap is equipped with a substantially U-shaped binding clip 14 preferably of metal bent around adjacent margins of the strap to overlie the contiguous end thereof with the legs of the clip extending longitudinally of the strap. Fitted through the strap between the said legs, is a metal eyelet 15 having its ends overturned for connecting the eyelet with the strap. Swiveled in the said eyelet and extending loosely through the bight of the clip 14, is a link 16 and connected to the outer end of the said link is a suitable snap or attaching device 17. It will be observed that by this arrangement the snap 17 with the link 16 may be turned upon the strap and by connecting the said link with the eyelet 15, the link cannot easily pull out. Furthermore, it will be observed that the bight of the clip 14 will co-operate with the said eyelet to support the link upon the strap with the legs of the clip holding the material of the strap from spreading at the eyelet to release the eyelet.

In use, the snap end of the strap is threaded through the buckle 11 in the manner shown in Fig. 1 with the teeth 13 of the catch 12 engaging with the strap for holding the buckle at adjustment. By sliding the buckle longitudinally upon the strap, the band may be adjustably fitted about the arm or other part of the person with the free end of the strap depending to receive a card case as conventionally illustrated at 18, a pocket-book or other similar article. For connecting the card case with the band, the snap 17 may be hooked in the ring of the said case with the case thus securely attached to the band to be safely carried thereby.

In some instances, it may be desired to form a loop of the free end of the strap and to accomplish this result, the snap 17 is hooked upon one end of the buckle 11, as illustrated in Fig. 2 to form a loop 19. The ring of a powder box as conventionally illustrated at 20 in the drawings may be connected with this loop when the box may be safely carried by the band. It will, of

course, be understood that any other appropriate article may be connected with the loop 19 in a similar manner. The band, when not being used for carrying articles, 5 may be employed as an ordinary strap, the type of buckle employed making it possible to adjustably fit the strap tightly about different objects without reference to any variation in the size of the said objects. Furthermore, owing to the nature of the buckle, the 10 band may be easily adjusted about the arm or other part of the person to fit comfortable thereon. In some instances, it might be found desirable to thread the band through 15 a button hole in the clothing for connecting the band with the person. The band is of such nature that it may be easily so arranged with the free end of the band depending for receiving the article to be carried there- 20 by. In other instances, it might be desired to connect the snap 17 directly with the buckle without passing the intermediate portion of the band through the buckle. In this way, the length of the band would be 25 formed into a continuous loop to be suitably engaged with an article or object with the said loop forming an easy means for carrying the said article or object.

It will, therefore be seen that I provide a 30 particularly efficient construction for the purpose set forth and while I have indicated various different ways in which the band may be employed in use, still, it will be understood

that the said band may be employed in various different other ways not necessary to 35 be herein mentioned.

Having thus described the invention, what is claimed as new is:

1. A device of the character described including a suspension element, an eyelet extending through and connected thereto, an attaching device, and means connecting the said attaching device with the said element and engaged with said eyelet with the said means disposed in a plane with the said 45 element.

2. A device of the character described including a suspension element, a marginal binding clip carried thereby, an eyelet fitted through the said element, an attaching device, and a link connected to the said attaching device and swiveled in the said eyelet with the said link fitted freely through the said clip.

3. A device of the character described including a suspension element, an attaching device, means embedded in the suspension element, means connecting the attaching device with the said element and swiveled upon the said first mentioned means, and means carried by the said element and rotatably receiving the said second mentioned means intermediate its ends to provide a guide and support therefor.

In testimony whereof I affix my signature.
ERNEST MAKER. [L.S.]
